UNITED STATES PATENT OFFICE.

SAMUEL A. PERRY, OF SAN FRANCISCO, CALIFORNIA.

MACHINE FOR MAKING PICTURE-MOLDINGS.

SPECIFICATION forming part of Letters Patent No. 341,049, dated May 4, 1886.

Application filed July 30, 1885. Serial No. 173,071. (No model.)

To all whom it may concern:

Be it known that I, SAMUEL A. PERRY, of the city and county of San Francisco, State of California, have invented an Improvement in 5 Machines for Making Picture-Moldings; and I hereby declare the following to be a full, clear, and exact description of the same.

My invention relates to that class of machines for making picture-moldings in which a pattern-roller and an underlying feed-roller are rotated in opposite directions, and the plastic material is passed between them.

My invention consists in the novel construction by which the pattern-roller may be readily removed for the substitution of another with a different pattern, in the arrangement of power-transmitting gears between the two rollers, which permit the vertical adjustment of the pattern-roller, still preserving their engagement or mesh, and in the general construction of the machine.

The object of my invention is to provide a simple and serviceable machine of this class.

Referring to the accompanying drawings, 25 Figure 1 is a perspective view of my machine, showing the plastic material being fed through. Fig. 2 is a vertical cross-section through the feed-roller and its shaft. Fig. 3 is a perspective view of the adjustable sleeves. Fig. 4 is 30 an elevation showing the arrangement of gears.

A is a bench or frame, from which rise slotted standards B, in which the vertically-adjustable boxes C are mounted and are adapted to slide.

35 D is a roller, having formed upon its periphery any suitable pattern.

E is a roller or drum mounted in a transverse slot in the bench A, and lies directly below the pattern-roller D.

40 The pattern-roller is mounted in the boxes C in the following manner, (shown particularly in Fig. 2: d is a shaft, which passes through the center of the roller and the vertically-adjustable boxes C, and is provided with nuts 45 d^b on its ends. Upon the shaft is journaled a sleeve, d', to which the pattern-roller D is keyed or otherwise secured. Journaled in one of the boxes C, and surrounding one end of the shaft d, is a clutch-sleeve, d², the inner end or 50 head of which is provided with notches d³. The adjacent end of the sleeve d' is provided

with small lugs or pins d⁴, which are adapted to fit in the notches of the clutch-sleeve. The object of this construction is to facilitate the removal of the pattern-roller for the substitution of one of a different pattern, and is thus accomplished: The nut on the end of the shaft being loosened, said shaft is pulled out, and the sleeve d' may then be disengaged from the clutch-sleeve. The roller can be removed from 55 its sleeve by taking out its key or other fastening. To put another in place, it is keyed on the sleeve d', which is then caused to engage the clutch-sleeve d², and the shaft d' is passed through both sleeves and its nut is tightened 60 up again. This enables me to use any character of pattern-roller without loss of time. The pattern-roller D is vertically adjustable by means of the screws F, passing down through the standards B and connected with the boxes 70 C. The upper ends of the screws are provided with pinions g, which mesh with a central spur-wheel, G, on a shaft, H, having a crank, h. By operating the crank-wheel the screws F are moved up and down to vertically adjust 75 the pattern-roller. On the end of the feed-roller shaft is a crank, O.

The means for transmitting power from the feed-roller to the pattern-roller are as follows: On one end of the shaft of the feed-roller E, 80 Fig. 4, is a pinion, I, and on the end of the clutch-sleeve d', which actuates the pattern-roller, is a pinion, J. Pivoted on the shaft of the feed-roller is a curved double or slotted link, K, in which is pivoted a pinion, L, and 85 a pinion, M, the former of which meshes with the pinion I and the latter with the pinion J. Said pinions L and M mesh also with each other, thus forming a connected chain of gearing. From the upper end of the link K extends a pivoted retaining-link, N, to the shaft of the pattern-roller. When the pattern-roller D is raised, the pivoted link K is drawn in to 90 keep its pinions M and L to their engagements, and when said roller is lowered the reverse movement of link K takes place, whereby the engagement of the gears is maintained. 95

The operation of my machine is as follows: The plastic material is placed upon a strip of suitable length, and is fed through between the roller E and the roller D, whereby the material is molded by the latter roller. By reason

of the adjustment of the pattern-roller moldings of different thicknesses may be passed through, the limits of adjustment of said roller being sufficient for any case, and the machine 5 continues to be operative, no matter how great the adjustment, because of the system of gears, which maintain their mesh, as described.

Having thus described my invention, what I 10 claim as new, and desire to secure by Letters Patent, is—

1. In a machine for making picture-moldings, the pattern-roller D, in combination with the removable supporting-shaft d, the sleeve d', journaled on the shaft and carrying the pattern-roller, and the rotating clutch-sleeve d², journaled on the shaft and engaging the sleeve d', substantially as herein described.

2. In a machine for making picture-moldings, the pattern-roller D, in combination with the removable supporting-shaft d, the sleeve d', journaled on said shaft and carrying the pattern-roller, said sleeve having lugs d⁴ on its end, and the clutch-sleeve d², to which power is applied, and having the notches d³ in its inner end, with which lugs of sleeve d' engage, substantially as herein described.

3. In a machine for making picture-moldings, the slotted standards B of a frame, the vertically adjustable or sliding boxes C in said standards, and the removable shaft d in the boxes, in combination with the pattern-roller D, the sleeve d', carrying the roller and journaled on the shaft, and the rotating clutch-sleeve d², journaled in one of the boxes and on the shaft, and engaging the sleeve d', substantially as herein described.

4. In a machine for making picture-moldings, the feed-roller E, to which power is applied, and the vertically-adjustable pattern-

roller D, mounted above, in combination with 40 the power-transmitting devices between said rollers, consisting of the pinion I on the feed-roller shaft, the pinion J, actuating the pattern-roller, and the adjustable intermediate pinions, L and M, substantially as herein de- 45 scribed.

5. In a machine for making picture-moldings, the feed-roller E, to which power is applied, and the vertically-adjustable pattern-roller D above, in combination with the means 50 by which the power of the feed-roller E is transmitted to the pattern-roller, consisting of the pinion I on the feed-roller shaft, the pinion J, by which the pattern-roller is driven, the intermediate pinions, L and M, the link K, 55 pivoted on the feed-roller shaft and carrying the intermediate pinions, and the pivoted retaining-link N from link K to the shaft of the pattern-roller, substantially as herein described.

6. A machine for making picture-moldings, comprising the bench A, having standards B, the feed-roller E, mounted transversely in a slot in the bench, the removable pattern-roller D, and vertically-adjustable boxes C in the 65 standards, and carrying the axis or shaft of the pattern-roller, the crank O and pinion I on the feed-roller shaft, the pinion J, actuating the pattern-roller, and the adjustable intermediate pinions, L M, all arranged and 70 adapted to operate substantially as herein described.

In witness whereof I have hereunto set my hand.

SAMUEL A. PERRY.
